UNITED STATES PATENT OFFICE.

CHARLES F. RAYBURN, OF MOSCOW, IDAHO.

EXCAVATING MACHINE.

Application filed February 24, 1921. Serial No. 447,404.

To all whom it may concern:

Be it known that I, CHARLES F. RAYBURN, a citizen of the United States, and a resident of Moscow, in the county of Latah and

State of Idaho, have invented certain new and useful Improvements in Excavating Machines, of which the following is a specification.

My invention relates to improvements in excavating machines of that type in which the digging and transporting mechanism is operated from a distance by means of a drag line, and is suspended during its journeys and operations on another line known as a slack-cable, or operated suspended from a boom of derrick or crane and hence operated as a circle drag line excavator, and has reference more particularly to that type in which the digging and dumping are accomplished without the use of tripping mechanism.

An object of my invention is to provide an excavating machine that performs three distinct and simultaneous actions in the operation of digging, of being lifted out, and when dumping.

Another object of the invention is to provide an excavating device by which dumping can be done very speedily.

Another object is to provide an excavating machine that cleans itself by and during the dumping action.

Another object is to produce an excavating machine that may be dumped at any point, at any speed, and at the will of the operator without the aid of auxiliary devices on the cable.

With these and other objects in view my invention consists in certain features of construction, arrangement and combination of parts as will hereinafter be fully described and pointed out in the claims, reference being had to the accompanying drawings in which—

Figure 1 is a side elevation showing traveling and digging position of the excavator.

Figure 2 is a side view showing the final dumping and returning position.

Figure 3 is a rear end elevation, and

Figure 4 is a front end elevation.

Figure 5 is a side elevation showing relative position of parts when in digging operation.

In the present embodiment of my invention, the excavator as a whole is supported by a suitable slack-cable A' said cable be-

ing anchored at one end to a suitable dead-man, thence passing over a block at the top of a mast, and its other end connected to the drum of a hoisting engine.

A carriage is so mounted as to travel on the cable and includes a longitudinal center tie-bar 1 made up of two inwardly turned channel bars having a hardwood timber between them. This tie-bar constitutes the backbone of the carriage and to its front ends and the center of its sides are secured two irregular shaped forward brackets 2 which extend upwardly and downwardly and at angles to the center tie bar 1. Between the upper ends of said brackets is journaled the front carriage traveling wheel or pulley 4 which is grooved as shown, and between the lower ends of said brackets 2 is journaled the grooved carriage fulcrum pulley 7.

Extending across these brackets 2 at their front ends and on their outer surfaces, channel iron braces 8 are secured at obtuse angles to the longitudinal center of the bar 1, the purpose of said braces being to add strength to forward braces 2 and to provide securing means for the oil casting boxes a' and b', these boxes lubricating respectively the fulcrum pulley 7 and traveling wheel 4.

The rear brackets 3 which are irregular in shape are secured to the rear and the middle of the tie bar 1 at the sides thereof; the brackets 3 are made secure to the center tie bar below their centers and their lower end portions 3' or are bent outwardly so that they will assist the carriage to rest in upright position when the excavator is digging; and also for the purpose of allowing connecting chains 17 to run in the grooved periphery of fulcrum pulleys 6.

Between the ends of upper parts of rear brackets 3 and above the longitudinal center tie bar 1 is journaled the grooved wheel 5 which is the rear traveling wheel of the carriage. Below the center tie bar 1 and between the lower extended leg portions 3' is secured the rear lower carriage brace 32, see Fig. 3. The brace fills the space formed by the outwardly extending end portions 3' and is secured to the lower side of the center bar 1 at its middle or thereabout, and is also secured to the rear of the center tie-bar 1 between rear carriage brackets 3 as shown in Figure 3.

To rear carriage brackets 3 and forming an obtuse angle to the center tie bar 1, the

rear channel iron braces 10 are secured, the purpose of said braces being to strengthen the rear carriage brackets 3 and the rear part of the center tie-bar. They also provide means by which oiling casting C' may be secured for oiling the rear carriage traveling wheel 5.

Channel iron braces 12 extend between channel iron brackets 8 and 10 flush with the sides of said brackets and parallel with the center tie-bar with their faces flush with the outer surface of the forward carriage brackets 2 and rear carriage brackets 3, and are secured in such relation for the purpose of strengthening the center tie-bar and the central portions of forward and rear brackets as shown in Figure 1.

Extending across the space at the outer upper face of brackets 2 and the outer upper face of brackets 3, and between front braces 8 and rear carriage braces 10 are braces 9 which are secured in such position; the purpose of the braces 9 is to strengthen both the forward and rear carriage brackets at their upper ends, and to relieve strain on the center tie bar 1.

To the sides of the rear carriage braces 3 which extend outwardly and downwardly in the same plane as the rear carriage legs are secured brackets 11 within which are mounted the fulcrum pulleys 6.

The bucket which constitutes an important and material feature of my invention comprises a bottom wall 28, side walls 27, and a rear wall 29, the bottom wall being provided with teeth 31 which are secured to the front end of the bottom wall, and it should be noted that the side walls 27 extend well beyond the bottom wall at the front and well beyond the ends of the teeth 31, as shown in Figure 1, the purpose being to obtain leverage.

The side walls 27 are connected at their upper front ends by a channeled cross bar 33; at its middle this bar has cut away a portion of the forward and rearward sides between which are mounted two upright braces 34 and riveted securely to the sides of and bottom of said cross piece 33.

A grooved fulcrum pulley 13 is journaled between the two upright braces 34. To the outer faces of side walls 27 are secured the reinforcing plates 27^a, 27^b, 27^c, 27^d and 27^e and to the bottom wall 28 at its two rear corners are secured the reinforcing shoes 30. To the upright rectangular rear walls of the bucket at the two upper outer corners are secured the bracket bumpers 18, and to the upper ends of these bumpers are secured by suitable means the rear end of rods 15, said rods being suitably spaced from the associated walls of the bucket to provide clearance for the movement of links 16 slidably mounted thereon.

The forward end of each rod 15 is thread-

ed through a guide bracket 14 and each rod is provided with a pair of lock nuts 15^a and 15^b to properly hold the same against movement with respect to the associated bracket 14 and also to permit adjustable longitudinal movement of these rods.

A brace 26 extends across the upper part of the bucket and is secured to side walls 27 to the rear of the brackets 14, this brace serving the purpose of strengthening and stiffening the upper middle portion of the bucket and also provides a support for the carriage during digging operation to keep the fulcrum wheels out of the material being excavated, and to form means on which the rear of the carriage may rest when in digging position. The manner of connecting the carrying member and the bucket or digging member is by means of the connecting fulcrum chain 17 the forward ends of which are connected to the links 16 which have been put in place on rods 15. These chains extend upwardly and inwardly and pass over fulcrum wheels 6 and then pass downwardly and outwardly over the rear walls 29 and are connected by means of swivel links 19 to the stationary shackles or clips 20 securely fastened to the outer surface of rear walls 29 at the lower outer corners thereof. A drag-line or hauling cable is connected to a swivel 21 and to this swivel is connected the chain 23 which passes over the carriage fulcrum pulley 7 downwardly and about the bucket fulcrum pulley 13; and then passes upwardly and is connected with the eye-bolt 24 which is suitably secured to the tie-bar 1 of the carriage.

The adjusting or lifting chain 23, has its one end attached to the under side of the carriage by means of an eye bolt 24 secured in the tie-bar 1, thence passing downward and forward and about the fulcrum pulley 13 carried by the bucket, thence upward and over the fulcrum pulley 7 depending from the forward end of the carriage thence forward and having its other end connected to the link or swivel 21 secured to the hauling cable or drag line D. Said center or adjusting chain 23 serves three offices, namely: as an adjusting chain to adjust the carriage relatively to the digging member or bucket, and keeping it so when the bucket is in digging position; as a pull line, as in Figure 1, and as a dumping line.

The bridle chains 22, which must be somewhat shorter than chain 23 have their one end attached by a shackle 25, or other suitable fastenings, to the exterior of the front ends of the side walls 27 of the bucket, and their other end connected to said swivel 21. Said bridle chains serve one purpose as a loading medium, and are then put under tension.

When being lifted and journeying to

dumping point, the carriage and digging member are so connected at their respective fronts and rears that the strain exerted by the drag line will be exerted on the different 5 parts of the chain 23, the strain also falling on the connecting chains, thus leading the bridle chains slack.

With the strain now falling on the center chain, the forward end of the bucket moved 10 upwardly and the bucket as a whole moves slightly rearwardly. The forward end of said member is lifted first and as the rear is elevated the links 16 seek the position as 15 shown in Figure 1 due to a strain exerted to connecting chains.

Having now fully described the construction of my invention and the arrangement of its parts, I will now explain the manner of its operation. Assuming the bucket is in 20 the digging position, as shown Figure 5 it will be noticed that it is sitting on the ground to be excavated, the carriage sitting on it supported by the central brace 26, the fulcrum pulleys 6 resting on the fulcrum chains 17 25 lying across said brace and the fulcrum pulley 7 resting on the adjusting chain 23. To start digging the operator begins to wind up the drag line D, hauling it forward until it puts the bridle chains 22 under tension as 30 shown in Figure 5, thereby dragging the bucket forward and filling it with earth. As soon as the bucket is filled, or shortly before, the operator begins winding up the cable A', thus raising it, and with it the carriage. As the carriage rises, the chains depending from it become taut and cause the bucket to rise also. At this point it will be 35 noticed that the fulcrum pulleys 7 and 13 tend to part company, and continue to do so until the pull of the drag line is communicated to chain 23 and tension on the bridle 40 22 is released, which condition continues until the excavator returns again to the digging position. It will also here be noticed 45 that the extent to which said pulleys 7 and 13 part company depends upon the length of the adjusting chain 23 relative to that of the bridle chains 22, the shorter the former compared to the latter the closer will be the 50 companionship during the journey and the higher will be the traveling position of the front of the bucket, and the less the danger of spilling the contents enroute. It will also be further noticed that as the tension 55 due to the pull of the drag-line D is shifted from the bridle chains 22 to the adjusting chain 23, said pulleys are being brought together thereby, the carriage is being drawn forward relatively to the bucket until the rear fulcrum pulleys of the former are approximately over the center of the latter, at the same time said rear fulcrum pulleys 6 are moving forward relatively to the traveller-bars 15 and tugging 60 at the fulcrum chains 17 with which they are

in engagement, thus causing the traveller links 16 to slide forward on the traveller bar 15 until they strike the brackets 14, at which time the several parts assume the position shown in Figure 1, which position is maintained by continued pull on the drag-line until the bucket has reached the proper place for dumping, the slack-cable having been gradually raised to the desired height determined by the operator, as the bucket has 70 75 made its journey.

During this journey, it should be noticed, the center of gravity of the bucket and its load has been practically under the fulcrum pulleys 6, which constitute the main upper points of suspension, the load being thus nearly in balance, with but a small portion of it supported by the forward fulcrum pulley 7 and the chain 23. At the same time the rear fulcrum chains 17 occupy oblique 80 85 positions, sloping rearwardly, downwardly and outwardly, thus tending to pull the bucket forward and upwardly as shown in Figure 1.

As soon as the bucket has reached the 90 point for dumping, the operator releases the pull on drag-line and the tension on the adjusting chain 23; the carriage ceases to advance, owing to the resistance of the slack-cable, the bucket continues to advance owing 95 to its momentum, shifting the center of gravity far forward of the point of suspension, the tension of the rear fulcrum chains aiding; the forward end of the bucket immediately falls because of the great unbalance 100 of the load, the traveller links 17 slip toward the rear of the traveler bars 15, thus letting the rear end of the bucket drop and hastening its fall to the vertical position as shown in Figure 2, in which position it immediately retreats down the slack-cable to a point above the place of excavation, the operator controlling the speed of return by suitable braking means. As the 105 bucket fell to the vertical position, its load, of course was discharged, the discharge being rendered the more complete by the action of the traveller links 16 in passing the bend in the traveller-bars 15, an additional 110 jolt and lurch forward being given as the links 16 strike the bumper brackets 18, a series of vibrations being set up in the bucket whereby any material that is inclined to adhere to its walls is shaken loose.

As soon as the bucket has retreated as far 120 as desired, the operator causes a pull to be exerted on the drag-line causing adjusting chain 23 (which now for a short space becomes a lifting chain as well) to raise the now depending forward end of the bucket 125 and bringing it to the horizontal position shown in Figure 1, the bucket again retreating rearwardly relative to the carriage, the sliding links 16 again slipping forward on the travelling-bars 15, the fulcrum chains 130

17 again assuming their tension and oblique positions, as shown in Figure 1, and the center of gravity of bucket being again brought under the rear fulcrum pulleys, whereupon, 5 or just previously, the operator releases and lowers the cable until the bucket reaches the ground, the carriage again rests upon the bucket, and the bucket is ready to be again drawn forward in the digging operation in 10 the same manner as before, a cycle of operations having been completed.

With an excavating machine constructed as herein set forth dumping can be accomplished at any point under the slack cable 15 at the highest possible speed, and at the will of the operator from his position at the power end thereof.

The digging member or bucket will free 20 itself from boulders, or other undigable, unseen objects by slackening off the drag line and raising slack cable. When undergoing such an operation the machine takes the dumping position.

I claim:—

25 1. In an excavating machine, the combination with a supporting cable, a traveling carriage thereon, said carriage comprising forward and rear brackets, and a central tie bar connecting the same, means at the upper ends of the forward and rear brackets 30 for supporting the carriage on the cable, pulleys carried at the lower ends of said brackets, connecting chains passing over said pulleys for flexibly supporting a digging member or bucket, a pulley carried at the forward end of the digging member, traveller bars carried by the digging member, chains passing over the pulleys at the lower end of the rear bracket, said chains 35 having slideable connection at one end with said traveller bars, and flexibly connected at the other end to the rear of the digging member, and a drag line having flexible connection with the front of the digging member 40 and the forward connecting chain.

45 2. In an excavating machine, the combination with a supporting cable, a carriage traveling on said cable, a digging member or bucket, a drag line, a lifting and adjusting chain flexibly connected with said drag line, bridle chains flexibly connected at one end to the forward end of the digging member and at their opposite ends to said drag line, a fulcrum pulley carried at the forward 50 end of the bucket, a fulcrum pulley carried at the forward lower end of the carriage, said lifting and adjusting chain threading around said fulcrum pulleys and stationarily secured at its opposite end to the said carriage, traveller bars mounted on the side walls of the bucket and bumper brackets at the rear ends of said bars, obliquely mounted fulcrum pulleys carried at the rear lower 55 end of carriage, and chains running over said fulcrum pulleys, one end of each of said

chains slidably engaging the said traveller bars, and the opposite ends flexibly connected with the rear wall of the bucket at its lower corners.

3. In an excavating machine in combination, a supporting cable, a trolley carriage supported thereon, said carriage comprising forward and rear convergent brackets and a center tie bar, a fulcrum pulley carried at the lower end of the forward bracket, and 70 a pair of obliquely mounted fulcrum pulleys at the lower end of the rear bracket, said last named pulleys disposed on opposite sides of longitudinal center of the carriage, a digging member or bucket comprising a 80 rear wall, a bottom wall, and side walls, a fulcrum pulley mounted at the central upper part of the front end of the bucket, traveller bars mounted on the upper ends of the side walls of the bucket, said bars 85 extending rearwardly from approximately the longitudinal center of the side walls, over and beyond the rear ends of said side walls, and terminating in abutments or bumpers, a lifting and adjusting drag chain 90 secured at one end to the carriage and weaving around the fulcrum pulleys at the forward ends of the carriage and bucket, and flexibly connected at its opposite end to a drag line, fulcrum chains flexibly connected 95 at one end to the rear walls of the bucket and extending convergently upwardly and over said obliquely mounted fulcrum pulleys at the lower ends of the carriage rear bracket, and slideably connected with the aforesaid 100 traveler bars.

4. An excavating machine, in combination, a slack supporting cable, a carriage provided with wheels travelling on said slack cable, pulley carrying brackets at the front and rear ends of the carriage, said brackets convergently disposed with respect to each other, a digging member, said digging member suspended from the carriage by a plurality of chain runs at its front end, and a pair 105 of chains connections at its rear end, and adjusting means provided for lengthening or shortening said pair of chains as substantially shown and described.

5. In an excavating machine, in combination, a slack supporting cable, a carriage mounted to travel thereon, a fulcrum pulley at the front lower end of said carriage, and obliquely mounted fulcrum pulleys at the rear lower end of the carriage, a digging member comprising a rear wall, a bottom wall and side walls, a fulcrum pulley mounted at the center upper part of the front of the bucket, traveler bars mounted on the upper edges of the side walls, and said bars 120 extending rearwardly from approximately the longitudinal center of side walls over and beyond the rear ends of said side walls terminating in abutments or bumpers, a lifting or center chain secured at one end 125

- to carriage and weaving around the fulcrum pulleys at the forward ends of the bucket and carriage and flexibly connected at its opposite end to a drag line, fulcrum chains 5 flexibly connected at one end to the rear lower outer corners of rear wall and extending convergently upward and over said obliquely mounted fulcrum pulleys at the lower ends of rear brackets and slidably connected to aforesaid traveler bars whereby said digging member journeys in an irregular elliptical path to accomplish the vertical excavating position as substantially shown and described.
- 15 6. In an excavating machine, in combination, a slack supporting cable, a travelling carriage thereon, said carriage comprising front and rear brackets, a center tie-bar, suitable braces at front and rear carrying 20 housings for pulley bearings, a longitudinal brace across the top, a horizontal brace between obliquely mounted rear lower pulleys, chains flexibly connecting and supporting a digging member on said carriage, said digging member comprising a rear wall, a bottom wall and side walls suitably braced at top, a lifting pulley at the center of the upper front end of the bucket, and traveler bars secured to the upper side walls and extending over the rear of the bucket, certain 30 of said connecting chains having slidable connection with said traveler bars.
7. In an excavating machine, and in combination with a cable supported travelling carriage provided with suitable hauling or drag line connections and a depending three pulley arrangement, a bucket flexibly suspended from said carriage and bearing at its forward end a supporting pulley, and at 35 its rear end a pair of traveller bars, one on either side, and provided at its forward end with a pair of chains, one on either side and having the one end connected to said bucket and the other end connected to said drag line, bumper brackets connecting said traveller bars to said bucket, and chains connecting said three pulley arrangement with 40 said supporting pulley and said traveller bars.
8. In an excavating machine, and in combination a supporting cable, a digging member suspended therefrom, a carriage member comprising a pair of forward brackets and a pair of rearward brackets secured respectively to the forward and rear ends of a central tie bar, and symmetrically disposed on either side thereof, and extending upwardly and downwardly therefrom, the depending portions of said rearward brackets divergent outwardly and downwardly at oblique angles with the sides of said central tie bar, a pair of grooved pulleys journalled between the upper ends of said forward and rearward pairs of brackets for the suspension of said carriage from the supporting cable, and in rolling contact therewith, a grooved pulley journalled between the lower ends of said forward brackets, and having chain connection with the forward end of said digging member and a suitable hauling cable, a pair of symmetrically disposed fulcrum pulleys mounted on the lower ends of said divergent portions of said rearward brackets, and having chain connections with the rearward portion of said digging member. 75
9. In an excavating machine, the combination of a travelling carriage, means for supporting said carriage on an aerial slack cable, a digging member suspended from said carriage, a front fulcrum pulley depending from the front end of said carriage, a pair of symmetrically disposed fulcrum pulleys journalled one at either lower rear corner of said carriage, variable and adjustable chain connection and suspension 80 between said front depending fulcrum pulley and the front end of said digging member, said chains connecting with a suitable hauling cable, and adjustable twin chain connections and suspension between said 85 pair of rear fulcrum pulleys and the rearward portion of said digging member. 90

CHARLES F. RAYBURN.
